UNITED STATES PATENT OFFICE.

SAMUEL G. SEARIGHT, OF ALPENA, MICHIGAN.

DESIGN FOR A HOLDER FOR SEWING UTENSILS.

Application filed March 12, 1924. Serial No. 8,909. Term of patent 14 years.

To all whom it may concern:

Be it known that I, SAMUEL G. SEARIGHT, a citizen of the United States, residing at Alpena, in the county of Alpena and State of Michigan, have invented a new, original, and ornamental Design for Holder for Sewing Utensils, of which the following is a specification, reference being had to the accompanying drawing, forming part thereof.

Figure 1 is a front elevation of the article holder.

Figure 2 is a side view thereof, and
Figure 3 is a plan view.

I claim:

The ornamental design for a holder for sewing utensils, as shown.

SAMUEL G. SEARIGHT.
